UNITED STATES PATENT OFFICE.

NIELS A. CHRISTENSEN, OF MILWAUKEE, WISCONSIN.

STARTING MECHANISM FOR INTERNAL-COMBUSTION ENGINES.

1,185,874.

Specification of Letters Patent.

Patented June 6, 1916.

Application filed June 1, 1911. Serial No. 630,630.

To all whom it may concern:

Be it known that I, NIELS A. CHRISTENSEN, a citizen of the Kingdom of Denmark, residing at Milwaukee, in the county of Milwaukee and State of Wisconsin, have invented certain new and useful Improvements in Starting Mechanism for Internal-Combustion Engines, of which the following is a specification, reference being had to the accompanying drawing, forming a part thereof.

This invention relates more particularly to compressed fluid as distinguished from mechanical and electrical starting devices.

In common with other devices of this class, its main object is to avoid the labor, trouble and danger incident to cranking and starting gasoline or internal combustion engines, and accessory to such main object, further objects of the invention are to introduce into the engine cylinder or cylinders on the power or firing strokes of the piston or pistons, in an uninterrupted series of successive charges, a starting fluid carbureted and compressed to the required degree for ignition and to successively ignite such carbureted charges in proper order on the firing strokes of the pistons without repeated manipulation of the apparatus, thereby utilizing the explosive energy of the starting fluid and avoiding the necessity of high initial compression thereof and a reservoir of large capacity therefor; to utilize the ordinary carbureter with which an internal combustion engine is provided without change or addition except a simple pipe connection for supplying the mixture to the compressor by which such mixture is compressed to the required degree for ignition; to render the starting mechanism including that for compressing the starting fluid inactive and thus avoid unnecessary wear thereof and waste of power during the normal operation of the engine, and generally to improve the construction and operation of apparatus for the main object above stated.

The invention consists in the construction, arrangement and combination of parts as hereinafter particularly described and defined in the claims.

In the accompanying drawings like characters designate the same or similar parts in the several figures.

Figure 1 is a side elevation of a four-cyl-

inder gasoline engine to which starting mechanism embodying the invention is applied, the auxiliary carbureter being shown in section and the reservoir broken away; Fig. 2 is an end elevation of the engine and starting mechanism, the compressor being shown in section; Fig. 3 is a section on the line A—A Fig. 5, of mechanism for controlling the operation of the distributing valves; Fig. 4 is a section on the line B—B Fig. 5, of the distributing valve mechanism, showing the valves in condition for action; Fig. 5 is a section on the line C—C Figs. 2 and 3, of said mechanism; Fig. 6 is a section on the line D—D Figs. 3 and 4; Fig. 7 is a section on the line E—E, Fig. 6, showing the distributing valves in inactive condition; Fig. 8 is a section on the line F—F, Figs. 2 and 9, of mechanism for starting and stopping the compressor; Fig. 9 is a section on the line G—G, Fig. 8; Fig. 10 is a section on the line H—H, Fig. 2, showing the outwardly closing spring-seated check valve in the starting connection of one of the cylinders; Fig. 11 is a section on the line I—I, Figs. 1 and 12, of the driver's or controlling valve; Fig. 12 is a section on the line J—J, Fig. 11; Fig. 13 is a section on the line K—K, Fig. 11; Fig. 14 is a section on the line L—L, Fig. 13, showing the driver's valve in position to connect the compressor with the reservoir; Fig. 15 is a similar section showing said valve in position to connect the reservoir with the distributing valves; Fig. 16 is a face view of the driver's valve seat; Fig. 17 is a face view of the driver's valve; Fig. 18 is a partial elevation and section showing a modified arrangement of the auxiliary carbureter; Fig. 19 is a section similar to Fig. 6, showing a modification of the distributing valve mechanism; Fig. 20 is a face view of a slight modification of the driver's valve seat such as is used with the arrangement of the auxiliary carbureter shown by Fig. 18; and Fig. 21 is a corresponding face view of a slight modification of the driver's valve used with the arrangement of carbureter and form of seat shown in Figs. 18 and 20.

Referring to Figs. 1 and 2 of the drawings, *a* designates the cylinders, in the present case cast in pairs, *b* the carbureter, *c* the throttle valve lever, *d* the manifold connecting the carbureter with the engine cylinders, *e* the magneto, and *f* the crank shaft of a

four-cylinder, four-cycle internal combustion engine, all of which may be of the usual construction and arrangement.

The ordinary electric ignition apparatus, such as the system comprising battery, magneto, induction coil and vibrator, with which engines of this class are usually equipped, is employed to ignite the carbureted fluid charges on successive firing strokes of the piston in starting the engine.

The starting mechanism comprises a compressor *g* having, as shown in Fig. 2, a piston *h* driven by a crank *i*, which may be connected manually or by an automatic controller with a rotating part of the engine such as the magneto driving shaft *j*. For this purpose a rotary and reciprocative clutch member *k* confined in a bearing or housing between the shaft of the crank *i* and the driving shaft *j*, is shown in Fig. 2. This clutch member is provided at one end with a tongue which is in constant engagement with a cross slot in the crank shaft and at the other end with a shorter tongue which is adapted to be shifted into and out of engagement with a cross slot in the driving shaft *j*. The member *k* is formed with circular rack teeth meshing with a pinion *l* on a short shaft arranged transversely to the axis of member *k* and provided as shown in Fig. 8, with a pinion *m*. The pinion *m* engages, as shown in Figs. 8 and 9, with rack teeth on a piston or movable part *n*, fitted to work in a cylinder or pressure chamber *o*, which is attached to the crank case or frame of the compressor. The piston or part *n* is preferably made tubular or hollow, being open at one end and closed at the other, which has a small opening or leak passage *p*. The cylinder or chamber *o* is provided at the end adjacent to the closed end of the piston with a port *q* and at the opposite end with a packing ring or disk *r*, against which the open end of the piston bears when it is shifted to start the compressor. When the piston is pressed, against this ring or disk, a fluid-tight joint is formed around the open end of the piston for a purpose hereinafter explained. The pinion shaft is provided with an arm or handle *s*, as shown in Figs. 1, 8 and 9, for manually operating the clutch member *k* and connecting the crank shaft of the compressor with the driving shaft *j*.

The compressor cylinder is connected by a suction pipe *t* with the carburetor *b* just below or in advance of the throttle valve which controls the supply of gas from the carburetor to the engine cylinders in the normal operation of the engine. The discharge port of the compressor provided as shown in Fig. 2 with a valve *u*, is connected as shown in Fig. 1, by a pipe *v* with the driver's valve *w*, and the pipe *v* is in turn connected by a branch *x* with the port *q* of the controller cylinder or chamber *o*. The pipe *v* is also

provided as shown in Fig. 1, with a valve-controlled connection *y*, whereby the compressor may be utilized for inflating automobile tires or for other purposes.

A reservoir *z* is connected as shown in Fig. 1, by a pipe *2* with the driver's valve *w*, so that by the proper adjustment of said valve as hereinafter explained, the reservoir may be charged by the compressor with air, gas or an explosive mixture at a pressure suitable for ignition by an electric spark, produced by the usual ignition apparatus such as a battery, induction coil and spark plugs with which engines of this class are provided.

So much of such an igniting apparatus consisting of a spark plug and conductor connection with the magneto, as is necessary for illustration, is illustrated in a conventional manner at *Ign.* in Fig. 2 of the drawing.

Referring to Figs. 3, 4, 5, 6 and 7 in connection with Figs. 1 and 2, the distributing valve mechanism for controlling and properly timing the delivery of the explosive starting mixture to the engine cylinders comprises four radially movable valves *3*, guided and provided with seats in radial chambers of a case *4*. The outer ends of the valve chambers are closed by caps *5*, and springs *6* interposed between the caps and the valves tend to close the valves and hold them against their seats. The valve chambers outside of the valve seats are connected by ports or passages *7* and *8* as shown in Figs. 3, 4 and 7, with a cylinder or pressure chamber *9*, with which the valve case is formed or provided. The valve chambers are connected inside of the valve seats by passages or ports *10*, shown in Figs. 3, 4, 6 and 7, and by pipes *11* shown in Figs. 1 and 2, with the several engine cylinders *a* in the proper firing order.

The cylinder or pressure chamber *9* is connected as shown in Fig. 1 with the driver's valve *w*, by a pipe *12*. As shown in Fig. 4, 5 and 6, a cam *13*, mounted on the end of the cam shaft *14* of the engine, projects into a central opening of the valve case *4* in position to engage with the inner ends of the stems of the distributing valves *3* and to open said valves one after another when they are released and in working condition.

To hold the distributing valves out of action during the normal operation of the engine and to release and permit their operation by the cam *13* for starting the engine, a cam *15* rotatably confined in the valve case *4* in line with the cam shaft *14*, is adapted, when turned in one direction, by engagement with lateral pins or projections *16* on the valve stems, to move and hold them out of the path of the cam *13* as shown in Fig. 7, thereby rendering the distributing valves inactive. When the cam *15* is turned in the

opposite direction into the position indicated by dotted lines in Fig. 3, out of engagement with the pins or projections 16, the valves 3 are moved inwardly by the springs 5 6 against their seats and their stems are carried back into the path of the cam 13. The cam 15 is formed or provided as shown in Figs. 3, 5 and 6, with a pinion 17, engaging with rack teeth on the stem of a piston 18, 10 fitted in the cylinder or pressure chamber 9, said stem being tubular and guided transversely to the axis of the cam 15 in a contracted extension of said cylinder or chamber, as shown in Fig. 3. A spring 19 inserted in the tubular stem of the piston 18 tends to shift said piston to the right, as shown in Fig. 3, and to turn the cam 15 into position as shown in Fig. 7, to hold the distributing valves 3 open and render them inactive. The port or passage 8 is arranged as 15 shown in Fig. 3, to be closed by the piston 18 when it is moved to the right and held in its normal position by the spring 19, and said piston is formed around its stem with a beveled face or shoulder which seats against a corresponding face or shoulder in the cylinder or chamber 9 when the piston is shifted to the extreme left and opens the port or 20 passage 8, thereby preventing the leakage of the compressed gas or explosive mixture into 25 and its escape from the opening in the valve case 4 containing the cams 13 and 15.

The connections of the pipes 11 are made with the several engine cylinders *a* through 30 inwardly opening spring-seated check valves 20, one of which is shown in section in Fig. 10, to close the starting connections of the engine during its normal operation when the distributing valves 3 are held open.

40 The driver's valve *w* as shown by Figs. 11, 12, 13, 14, 15 and 16, comprises a base plate 21, a seat 22, and a recessed cap or cover 23, forming with the seat a closed chamber and bolted therewith to the base plate 21. The 45 base plate 21 and the seat 22 are formed with a central opening 24, with which the pipe 2 is connected, as shown in Fig. 1. They are also formed with ports 25, 26, 27 and 28, the ports 25 and 27 being connected by the pipes 50 *v* and 12 respectively with the compressor *g* and with the pressure chamber 9 of the distributing valve controller. The ports 26 and 28, opening to the atmosphere, are exhaust ports. A rotary valve disk 29, having 55 a short stem fitted to turn in the central opening 24 in the valve seat, is formed as shown in Fig. 17, with a central port 30 passing through said stem and communicating with the opening 24 with which the reservoir *z* is connected. It is also formed 60 with a through port 31, and in its working face with cavities 32 and 33. The port 31 is adapted in one extreme position of said valve disk to register with the port 25 in the 65 valve seat 22, as shown in Fig. 14, and in

the other extreme position of said disk to register with the port 27 in said seat, as shown in Fig. 15. In the middle or neutral position of said valve disk the ports 25 and 26 are connected by the cavity 32, and the 70 ports 27 and 28 are connected by the cavity 33 while the port 31 is closed. The valve disk 29 is operated by a stem 34 which is fitted to turn in a tubular neck on the cap or cover 23 and provided at its outer end with 75 a handle 35.

To enrich the starting mixture, the apparatus is preferably provided with an auxiliary carbureter 36, which as shown in Fig. 1, may be located between the driver's valve *w* and the reservoir *z* and connected with the pipe 2 by branches 37 and 38. The branch 37 extends downwardly through the top nearly to the bottom of the carbureter and is provided with a check valve 39 which closes toward the reservoir *z*. The branch 38 leads outwardly from the upper part of the carbureter above the normal liquid level therein, and the pipe 2 is provided with a check valve 40 opening toward the reservoir *z*. By this arrangement of connections and check valves the compressed air, gas or mixture on its way from the compressor *g* to the reservoir *z*, flows through the pipe 2, which serves as a by-pass around the carbureter 36, the check valve 39 being closed and preventing flow in that direction through the carbureter. When however, the reservoir is connected through the driver's valve *w* with the distributing valve case 4, the compressed air, gas or mixture will pass by way of the branches 37 and 38 through the carbureter 36, the check valve 40 being closed and preventing its flow directly through the pipe 2. This carbureter is provided with a valve-controlled filling connection 42, by which it is supplied with gasoline from time to time as required. 100

In place of locating the auxiliary carbureter between the driver's valve *w* and the reservoir *z*, it may be located in the pipe connection 12 between the driver's valve and the distributing valves, as shown in Fig. 18. With this arrangement the by-pass around the carbureter may be omitted, and in order 110 to prevent the back flow of gasoline from the carbureter and its escape through the driver's valve, the exhaust port 28 in the valve seat 22 is closed or omitted, as shown in Fig. 20, and the cavity 33 in the valve disk 29 may be omitted, as shown in Fig. 21. 115

Instead of lifting and holding the distributing valves away from their seats in order to render them inactive during the normal operation of the engine, the cam by which they are actuated in starting the engine may be shifted out of operative position. 125

Referring to Fig. 19 showing a modification of the distributing valve actuating and 130

controlling mechanism, the cam 43 by which the distributing valves 3 are actuated for starting the engine, is mounted and movable endwise on a square stem 44, which is threaded in the end of the cam shaft 14 and secured in adjusted position by a jam nut 45. By loosening this nut the stem 44 may be turned in the shaft 14 and the angular adjustment of the cam 43 varied to properly time the opening of the valves 3.

10 A piston 46 is fitted in a cylinder or chamber 47 formed in the valve case 4 coaxial with the shaft 14, and the hub of the cam which projects outwardly beyond the stem 44 has a central pivot seated in or against the piston. The cam with the piston is thrust outward and held normally out of operative relation to the inwardly projecting stems of the valves 3, by a spring 48 inserted between the outer end of the stem 44 and the outer end of the hub of the cam. The cylinder or chamber is connected through a port 49 with the driver's valve *w*, by pipe 12, Fig. 1 or 18.

15 The inner end of the cam is beveled or inclined so that when it is shifted by the piston 46 into operative position it will thrust whichever of the valve stems may be in its path outward and open the corresponding valve 3. The inner end of the piston when it is thrust inwardly by the admission of compressed gas into the chamber 47 is pressed and held tightly against a seat or shoulder at the inner end of said chamber, thereby preventing the escape of gas through the opening in the valve case around the cam shaft. The piston in its outer and normal position closes the port 8 and in its inner position opens said port.

20 The apparatus hereinbefore described operates as follows: The reservoir *z* having been charged at a suitable pressure, say from 70 to 90 pounds, as indicated on a gage (not shown) by the compressor *g*, and the valve disk 29 being in its middle or neutral position, as shown in Figs. 1, 11, 12 and 13, closing the connection with said reservoir and connecting the compressor controller and the distributing valve controller with the atmosphere through the pipes *v* and 12, the ports 25 and 26 and cavity 32 and the ports 27 and 28 and cavity 33 respectively, to start the engine the disk 29 is turned by the handle 35 to the left into the position shown in Fig. 15. In this position the port 31 registering with the port 27, connects the reservoir *z* through the pipe 12 with the chamber 9, Fig. 3. The starting mixture or fluid being thus admitted under pressure to chamber 9 instantly shifts the piston 18 into the position shown in Fig. 3, against the tension of spring 19. The port 8 being opened the mixture passes thence through the ports or passages 7, Figs. 4 and 7, to the distributing valve chambers outside of the valves.

The shifting of the piston 18 into the position shown in Fig. 3, as above stated, operates through the pinion 17, Figs. 3, 5 and 6, to turn the cam 15 into the position indicated by dotted lines Fig. 3, thereby disengaging the pins 16 and releasing the distributing valves 3, all but one of which will be instantly closed by the springs 6, as shown in Fig. 4. One of said valves being held open by the engagement of its stem 75 with the high part of the cam 13, the mixture passes by way of the associated port or passage 10, pipe 11 and check valve 20, Figs. 1, 2, 3, 4 and 10, into the cylinder *a*, whose piston is on its power or firing stroke and in which a series of electric sparks are being produced by the igniting apparatus, in the usual way. In engines of this kind to which the starting mechanism herein described is applicable, the crank shaft naturally and 80 usually comes to rest within the range of about 135 degrees of its angular movement, so that the piston in one of the cylinders will almost invariably stand on its power or firing stroke in proper position for starting, and the circuit of the spark plug in that cylinder will be closed.

25 The explosive mixture or starting fluid upon entering the cylinder under the conditions above stated at an igniting pressure, will be ignited, and the force of the resulting explosion and expansion of the charge imparted to the piston will start the engine. As the crank shaft turns, the distributing valves 3 actuated one after another by the cam 13, function to admit the explosive mixture at an igniting pressure to the cylinders on the power or firing strokes of their pistons in the proper firing order. Very few impulses being sufficient to start the engine, the driver's valve will ordinarily be turned to starting position for an instant or a very short time only. When it is turned back to its middle or neutral position, thereby closing communication between the distributing valve mechanism and reservoir *z* and opening the pipe 12 to exhaust through the port 28, the piston 18, Fig. 3, will be relieved of pressure and shifted by the spring 19 back to its normal position, covering the port 8. This movement of the piston 18 operates through the pinion 17 to turn the cam 15 into the position shown in Fig. 7, in which by engagement with the pins 16 it forces the stems of the distributing valves 3 out of the path of the cam 13. The distributing valves 3 are thus held open and inactive during the normal operation of the engine. The air forming a part of the starting mixture may be carbureted either before or after compression, or both before and after compression.

30 In order to insure a rich mixture for the first charge in starting, the apparatus is preferably supplied with an auxiliary car-

bureter located and connected so that the preliminary mixture will pass through it on its way from the reservoir z to the engine. It may be located and connected as shown in Fig. 1, between the reservoir and driver's valve, or it may be located and connected as shown in Fig. 18, between the distributing valve mechanism and the driver's valve, or it may be dispensed with altogether, the main or regular carbureter b of the engine being depended upon to supply the requisite proportion of oil vapor or fuel to the mixture before compression thereof.

15 By connecting the compressor g on the suction side with the carbureter b just below or ahead of the throttle valve, the reservoir z will be charged at the requisite pressure with an explosive mixture such as is supplied to the engine in its normal operation, without change in or addition to the carbureter except a connection for the compressor.

To charge the reservoir z , the driver's valve is turned while the engine is running, 25 into the position shown in Fig. 14, in which the port 31 of the disk 29 registers with the port 25 of the seat 22, thereby connecting the reservoir through the pipe v with the discharge of the compressor g , and also 30 through the branch pipe x and the port q , Figs. 1 and 9, with the cylinder or chamber o . If there is sufficient pressure in the reservoir it will shift the piston n to its extreme 35 position away from the port q , thereby operating through the pinions m and l to shift the clutch member k into engagement with the driving shaft j . The compressor will thus be automatically started by the proper manipulation of the driver's valve to 40 charge the reservoir. If however, there is insufficient pressure in the reservoir to start the pump in this manner, the piston n will be shifted manually by means of the arm or handle s , which is turned to the right or 45 clockwise, for this purpose. When the desired pressure as indicated by the gage, has been reached in the reservoir z , the driver's valve is turned into its middle or neutral position, Figs. 11, 12 and 13, thereby closing 50 communication between the reservoir and compressor and connecting the pipe v through the port 25 and cavity 32 with the exhaust port 26. The compressed fluid being thus released from the chamber o 55 through the port q , the expansion of the gas confined in the hollow piston n which is sealed at its open end by the packing ring or disk r , will shift said piston back to its original or normal position shown in Fig. 9, 60 the confined gas escaping gradually through the restricted passage p till the pressure within the piston is reduced to that of the atmosphere. This movement of the piston n operates through the pinions m and l to shift 65 the clutch k out of engagement with the driv-

ing shaft j and thus automatically stops the compressor.

The apparatus may be provided with an automatic pressure regulating device by which when the pressure in the reservoir z 70 attains a certain limit, the chamber o will be opened to exhaust through the port q and the compressor stopped without manipulation of the driver's valve or attention on the part of the driver.

With the modified form of distributing valve mechanism and controlling device shown in Fig. 19 the operation of the apparatus is substantially the same as hereinbefore described in connection with the distributing valve mechanism and controlling device shown in Figs. 3, 4, 5, 6 and 7. Normally the valve actuating cam 43 is held by the spring 48, as shown in Fig. 19, out of operative relation to the stems of the distributing valves 3, which are held closed by the springs 6.

In starting the engine when the compressed gas or mixture is admitted from the reservoir z through the driver's valve w , 90 pipe 12 and port 49 into the cylinder or chamber 47, the piston 46 with the cam 43 is shifted to the right, thus carrying the cam into operative position relative to the stems of the valves 3 and opening whichever 95 of said valves is connected with the cylinder in which the piston is on its power or firing stroke. As soon as the engine is in motion the valves 3 function, as hereinbefore explained, to admit the compressed explosive mixture to the several cylinders in the proper firing order on the power stroke of their pistons. When the driver's valve is turned back to its middle or neutral position 100 after starting the engine, and the compressed gas is released from the chamber 47, the cam 43 with the piston 46 will be forced back to its original inoperative position by the spring 48. When the piston 46 is shifted to the extreme right, it is seated against 110 the inwardly projecting shoulder at the inner end of the chamber 47 and thereby prevents leakage of the compressed explosive mixture through the opening in the valve case around the cam shaft 14. The piston 46 like the piston 18 in the other form of controlling device hereinbefore described, controls 115 the port or passage 8 through which the compressed mixture is delivered to the distributing valve chambers outside of the valve seats.

With the arrangement of auxiliary carbureter shown in Fig. 18 and the modified form of driver's valve shown in Figs. 20 and 21, the operation of the starting apparatus is substantially the same as hereinbefore explained, except that the compressed air or mixture on its way from the reservoir z to the engine first passes through the driver's valve, and when said valve is turned 125

6
back to its middle or normal position the pipe 12 is not opened to exhaust, since without a return by-pass around the carbureter, the oil contained in the carbureter would 5 otherwise be forced out through the exhaust port. The gas confined in the chamber 9 or in the chamber 47 will, however, gradually leak therefrom when the connection with the reservoir 2 is closed at the driver's valve 10 w, so that the piston 18 or the piston 46 will in a short time be shifted back to its normal position and thus render the distributing valves inactive, as hereinbefore explained.

Various changes other than those hereinbefore mentioned, in the details of construction and arrangement of parts of the apparatus may be made within the principle and scope of the invention.

I claim:

20 1. In a starting mechanism for internal combustion engines, a reservoir for compressed fluid, a distributor connected with said reservoir and the engine cylinder, said distributor including valve actuating mechanism having a driving connection with the engine, and a distributor valve for admitting successive charges of fluid from the distributor to the engine cylinder on the firing stroke for starting the engine, means 25 controlling the connection between the distributor and the reservoir and controlling the operative connection between said valve actuating mechanism and the distributor valve, and an igniting device for igniting 30 the combustible charge on the firing stroke of the engine.

2. In a starting mechanism for internal combustion engines, a reservoir for compressed fluid, a distributor connected with 40 said reservoir and the engine cylinder, said distributor including valve actuating mechanism having a driving connection with the engine, and a distributor valve for admitting successive charges of fluid from the distributor to the engine cylinder on the firing stroke for starting the engine, a piston valve 45 operable by compressed fluid from the reservoir and controlling the connection between the distributor and the reservoir and controlling the operative connection between said valve actuating mechanism and the distributor valve, and an igniting device for igniting the combustible charge on the firing stroke of the engine.

55 3. In a starting mechanism for internal combustion engines, a reservoir and means for supplying the reservoir with compressed combustion supporting fluid, a distributor for compressed fluid connected with said 60 reservoir and the engine cylinder, a carbureter for supplying the compressed fluid with volatile fuel, a valve in the distributor for supplying successive charges of compressed fluid from the distributor to the engine cylinder on the firing stroke for start-

ing the engine, a valve controlling the connection between the distributor and the reservoir, and an igniting device for igniting the combustible charge on the firing stroke of the engine.

4. In a starting mechanism for internal combustion engines, a reservoir and means for supplying the reservoir with compressed combustion supporting fluid, a distributor for compressed fluid connected with said 70 reservoir and the engine cylinder, a carbureter for supplying the compressed fluid with volatile fuel, a valve in the distributor for supplying successive charges of compressed fluid from the distributor to the engine cylinder on its firing stroke for starting the engine, a valve operable by compressed fluid from the reservoir and controlling the connection between the distributor and the reservoir, and an igniting device for igniting the combustible charge on the firing stroke of the engine.

5. In a starting mechanism for internal combustion engines, a reservoir and means for supplying the reservoir with compressed combustion supporting fluid, a carbureter for supplying fuel for said fluid, a distributor connected with said reservoir and the engine cylinders, said distributor including valves for admitting charges of compressed fluid from the distributor into the engine cylinders, in succession, on the firing stroke of each piston, for starting the engine so long as the reservoir is in communication with the distributor, and means controlled 90 by fluid pressure from the reservoir for rendering the distributor valves active and inactive.

6. In starting mechanism for internal combustion engines the combination with an engine cylinder, piston and crank shaft; of a reservoir and means for supplying the reservoir with compressed combustion supporting fluid, distributing valve mechanism having an actuating connection with the engine of invariable angular relation to the crank shaft and adapted to admit compressed fluid from the reservoir into the cylinder in successive charges on the firing strokes of the piston, means for continuously supplying volatile fuel to said fluid to form an explosive mixture therewith, a driver's valve controlling the supply of compressed fluid from said reservoir to the engine, and ignition apparatus independent of the driver's valve and adapted while said valve remains open to automatically and successively ignite said charges in the cylinder on the firing strokes of the piston.

7. In starting mechanism for internal combustion engines the combination with a plurality of engine cylinders and pistons and a crank shaft, of a reservoir connected with the several cylinders and means for supplying the reservoir with compressed 125 fluid from the reservoir to the engine cylinder on the firing stroke for starting the engine.

- combustion supporting fluid, distributing valve mechanism having an actuating connection with the engine of invariable angular relation to the crank shaft and adapted 5 to admit compressed fluid from the reservoir into the several cylinders in an uninterrupted series of successive charges on the firing strokes of the pistons, means for continuously supplying volatile fuel to said fluid to 10 form an explosive mixture therewith, a driver's valve controlling the supply of compressed fluid from the reservoir to the distributing valve mechanism and thence to the cylinders, and ignition apparatus independent 15 of the driver's valve and adapted while said valve remains open to successively ignite said charges in the proper firing order in the cylinders on the firing strokes of their pistons.
- 20 8. In starting mechanism for internal combustion engines the combination with an engine cylinder, piston and crank shaft; of a reservoir and means for supplying the reservoir with compressed combustion supporting fluid, a distributing valve having an actuating connection with the engine of invariable angular relation to the crank shaft and adapted to admit compressed fluid from the reservoir into the cylinder in an uninterrupted 25 series of successive charges on the firing strokes of the piston, a driver's valve controlling the supply of compressed fluid from the reservoir to the distributing valve mechanism and thence to the cylinder, a carbureter for continuously supplying volatile fuel to said fluid to 30 form an explosive mixture therewith, ignition apparatus independent of the driver's valve and adapted while said valve remains open to successively ignite said charges on the firing strokes of the piston, and a valve independent of the driver's valve adapted to successively close the connection between the cylinder and distributing valve when explosions take place in 35 the cylinder while the driver's valve is open.
9. In starting apparatus the combination with a number of engine cylinders and pistons and a crank shaft; of a reservoir connected with the several cylinders and means 40 for supplying the reservoir with compressed combustion supporting fluid, distributing valve mechanism having an actuating connection with the engine of invariable angular relation to the crank shaft and adapted 45 to admit compressed fluid from the reservoir into the several cylinders in an uninterrupted series of successive charges on the firing strokes of the pistons, a driver's valve controlling the supply of compressed fluid from 50 the reservoir to the distributing valve mechanism and thence to the cylinders; a carbureter, ignition apparatus, and automatic valves independent of the driver's valve and adapted, respectively, while said valve remains open to continuously supply volatile 55 fuel to said fluid for forming an explosive mixture therewith, to successively ignite said charges, and to close the connections between the cylinders and distributing valve mechanism when explosions take place in 60 the cylinders.
10. In starting mechanism for an internal combustion engine, the combination of a compressor adapted to be driven by the engine, a reservoir supplied by the compressor with compressed combustion supporting fluid, a carbureter adapted to supply the starting fluid with volatile fuel, a distributing valve adapted to be driven by the engine and connected with the reservoir and with the engine, a driver's valve controlling the connection between the reservoir and distributing valve, and means operating under control of the driver's valve to start and stop the operation of the distributing valve 65 when the compressed starting fluid is admitted thereto and released therefrom.
11. In starting mechanism for an internal combustion engine, the combination of a compressor adapted to be driven by the engine, a reservoir supplied by the compressor with compressed combustion supporting fluid, a carbureter adapted to supply the starting fluid with volatile fuel, a distributing valve connected with the reservoir and with the engine, a driver's valve controlling the connection between the reservoir and the distributing valve, and means operating under the control of the driver's valve to automatically start and stop the compressor. 70
12. In starting mechanism for an internal combustion engine, the combination of a compressor, a reservoir connected with the compressor, a carbureter connected with the reservoir, a distributing valve, and an auxiliary carbureter through which the compressed starting mixture passes from the reservoir to the distributing valve. 75
13. In starting mechanism for an internal combustion engine, the combination with a carbureter of a compressor connected with said carbureter, a reservoir supplied by the compressor with compressed combustion supporting fluid, a distributing valve connected with the reservoir and with the engine, a driver's valve controlling the connection between the reservoir and the distributing valve, and an auxiliary carbureter and by-pass so arranged that the starting fluid will pass to the engine through said auxiliary carbureter and in the opposite direction through the by-pass independently of the auxiliary carbureter. 80
14. In starting mechanism for an internal combustion engine, the combination of a reservoir and means for supplying the reservoir with compressed combustion supporting fluid, a carbureter for supplying fuel for said fluid, a distributing valve adapted to be driven by the engine and connected with 85
15. In starting mechanism for an internal combustion engine, the combination of a compressor, a reservoir connected with the compressor, a carbureter connected with the reservoir, a distributing valve, and an auxiliary carbureter through which the compressed starting mixture passes from the reservoir to the distributing valve. 90
16. In starting mechanism for an internal combustion engine, the combination of a compressor, a reservoir connected with the compressor, a carbureter connected with the reservoir, a distributing valve, and an auxiliary carbureter through which the compressed starting mixture passes from the reservoir to the distributing valve. 95
17. In starting mechanism for an internal combustion engine, the combination of a compressor, a reservoir connected with the compressor, a carbureter connected with the reservoir, a distributing valve, and an auxiliary carbureter through which the compressed starting mixture passes from the reservoir to the distributing valve. 100
18. In starting mechanism for an internal combustion engine, the combination of a compressor, a reservoir connected with the compressor, a carbureter connected with the reservoir, a distributing valve, and an auxiliary carbureter through which the compressed starting mixture passes from the reservoir to the distributing valve. 105
19. In starting mechanism for an internal combustion engine, the combination of a compressor, a reservoir connected with the compressor, a carbureter connected with the reservoir, a distributing valve, and an auxiliary carbureter through which the compressed starting mixture passes from the reservoir to the distributing valve. 110
20. In starting mechanism for an internal combustion engine, the combination of a compressor, a reservoir connected with the compressor, a carbureter connected with the reservoir, a distributing valve, and an auxiliary carbureter through which the compressed starting mixture passes from the reservoir to the distributing valve. 115
21. In starting mechanism for an internal combustion engine, the combination of a compressor, a reservoir connected with the compressor, a carbureter connected with the reservoir, a distributing valve, and an auxiliary carbureter through which the compressed starting mixture passes from the reservoir to the distributing valve. 120
22. In starting mechanism for an internal combustion engine, the combination of a compressor, a reservoir connected with the compressor, a carbureter connected with the reservoir, a distributing valve, and an auxiliary carbureter through which the compressed starting mixture passes from the reservoir to the distributing valve. 125
23. In starting mechanism for an internal combustion engine, the combination of a compressor, a reservoir connected with the compressor, a carbureter connected with the reservoir, a distributing valve, and an auxiliary carbureter through which the compressed starting mixture passes from the reservoir to the distributing valve. 130

the reservoir and with the engine, a driver's valve controlling the connection between the reservoir and distributing valve, and means operating under the control of the driver's 5 valve to start and stop the operation of the distributing valve when the compressed starting fluid is admitted thereto and released therefrom.

15. In starting mechanism for an internal 10 combustion engine, the combination of a compressor adapted to be driven by the engine, a reservoir supplied by the compressor with compressed combustion supporting fluid, a carbureter for supplying fuel for 15 said fluid, a distributing valve connected with the reservoir and with the engine, a driver's valve controlling the connection between the reservoir and the distributing valve, and means operating under the control 20 of the driver's valve to automatically start and stop the compressor.

16. In starting mechanism for an internal combustion engine, the combination of a compressor adapted to be driven by the engine, a reservoir supplied by the compressor with compressed combustion supporting fluid, a distributing valve connected with the reservoir and with the engine, a driver's valve controlling the connection between the 25 reservoir and the distributing valve, means 30 operating under the control of the driver's valve to automatically start and stop the compressor, and means also operating under the control of the driver's valve to start and 35 stop the operation of the distributing valve when the compressed starting fluid is admitted thereto and cut off therefrom.

17. In starting mechanism for an internal 40 combustion engine, the combination of a reservoir and means for supplying the reservoir with compressed combustion supporting fluid, a carbureter connected with said reservoir to supply fuel for said fluid, a distributing valve adapted to be driven by 45 the engine and connected with the reservoir and with the engine, a driver's valve controlling the connection between the reservoir and distributing valve, and means operating under the control of the driver's 50 valve to start and stop the operation of the distributing valve when the compressed starting fluid is admitted thereto and cut off therefrom.

18. In starting mechanism for an internal 55 combustion engine, the combination of a compressor adapted to be driven by the engine, a reservoir supplied by the compressor with compressed combustion supporting fluid, a carbureter connected with the reservoir 60 to supply fuel for said fluid, a distributing valve connected with the reservoir and with the engine, a driver's valve controlling the connection between the reservoir and the distributing valve, and means operating un-

der the control of the driver's valve to automatically start and stop the compressor.

19. In starting mechanism for an internal combustion engine, the combination of a compressor, a reservoir supplied by the compressor with compressed combustion supporting fluid, a distributing valve connected with said reservoir and with the engine, a connection with the engine for actuating the distributing valve, a pressure chamber connected with the reservoir and 70 having a movable part adapted to render the distributing valve active or inactive, and a valve controlling the connection between said chamber and reservoir.

20. In starting mechanism for internal 80 combustion engines, the combination with the carbureter which supplies the engine during its normal operation with the requisite mixture of fuel and air, of a compressor having an actuating connection with 85 the engine and a suction connection with said carbureter, a reservoir connected with said compressor, a distributing valve connected with the reservoir and engine and adapted to be operated by the engine to admit the mixture to the engine on the power stroke of its piston, and a valve controlling the connection between the distributing valve and the reservoir.

21. In starting mechanism for internal 95 combustion engines, the combination with the carbureter which supplies the engine during its normal operation with a mixture of fuel and air, of a compressor having an actuating connection with the engine and a suction connection with said carbureter, a reservoir connected with said compressor, a distributing valve connected with the reservoir and engine and adapted to be operated by the engine to admit the mixture to the 100 engine on the power stroke of the piston, a valve controlling the connection between the distributing valve and the reservoir and an auxiliary carbureter through which the mixture passes from the reservoir to the engine.

22. In starting mechanism for an internal combustion engine having a number of cylinders, a reservoir and means for supplying the reservoir with compressed combustion 115 supporting fluid, a carbureter adapted to supply the starting fluid with volatile fuel, distributing valve mechanism connected with said reservoir and with the several engine cylinders, and operated in rotation 120 by the engine, ignition apparatus, and a valve operable by compressed fluid from the reservoir and controlling the connection between the distributing valve mechanism and said reservoir, said parts operating to automatically deliver into the engine cylinders 125 an uninterrupted series of carbureted fluid charges at igniting pressure and to suc-

sively ignite such charges in the proper order on the firing strokes of the pistons when the controlling valve is set and left in position to admit the compressed fluid 5 from the reservoir to the distributing valve mechanism.

23. In starting mechanism for internal combustion engines the combination of a reservoir and means for supplying the reservoir with compressed combustion supporting fluid, a carbureter adapted to supply said fluid with volatile fuel before it is delivered to the engine, a distributing valve connected with said reservoir and with the 15 engine cylinder and having a driving connection with the engine, an outwardly closing automatic check valve in the connection between the distributing valve and cylinder,

ignition apparatus, and a valve operable by compressed fluid from the reservoir and 20 controlling the connection between the distributing valve and the reservoir, said parts operating to automatically deliver into the cylinder an uninterrupted series of carbureted fluid charges on the firing strokes of 25 the piston when said controlling valve is set and left in position to admit the compressed fluid from said reservoir to the distributing valve.

In witness whereof I hereto affix my signature in presence of two witnesses. 30
